CLAIM

The ornamental design for a tent without supporting rods as shown and described.

DESCRIPTION

FIG. 1 is a front, right, top perspective view of a tent without supporting rods showing my new design;

FIG. 2 is a back, left, bottom perspective view thereof;

FIG. 3 is a tent without supporting rods as shown in FIG. 1, shown in an environment of use;

FIG. 4 is a front view thereof;

FIG. 5 is a back view thereof;

FIG. 6 is a left view thereof;

FIG. 7 is a right view thereof;

FIG. 8 is a top view thereof;

FIG. 9 is a bottom view thereof;

FIG. 10 is an enlarged view of the encircled area 10 of FIG. 1;

FIG. 11 is an enlarged view of the encircled area 11 of FIG. 1;

FIG. 12 is an enlarged view of the encircled area 12 of FIG. 1;

FIG. 13 is an enlarged view of the encircled area 13 of FIG. 2;

FIG. 14 is an enlarged view of the encircled area 14 of FIG. 2;

FIG. 15 is an enlarged view of the encircled area 15 of FIG. 2;

FIG. 16 is an enlarged view of the encircled area 16 of FIG. 3;

FIG. 17 is an enlarged view of the encircled area 17 of FIG. 3;

FIG. 18 is an enlarged view of the encircled area 18 of FIG. 4;

FIG. 19 is an enlarged view of the encircled area 19 of FIG. 5;

FIG. 20 is an enlarged view of the encircled area 20 of FIG. 6;

FIG. 21 is an enlarged view of the encircled area 21 of FIG. 9; and,

FIG. 22 is an enlarged view of the encircled area 22 of FIG. 9.

The broken lines shown on the drawings depict portions of the tent without supporting rods that form no part of the claimed design. In FIGS. 3, 16 and 17, the broken lines depict the environment in which the tent without supporting rods is used that form no part of the claimed design.
